UNITED STATES PATENT OFFICE.

IRWIN L. DUNN, OF MARIETTA, OHIO.

METHOD OF AND APPARATUS FOR STOPPING LEAKS IN THE CASING OF OIL AND GAS WELLS.

Application filed November 10, 1924. Serial No. 748,928.

To all whom it may concern:

Be it known that I, IRWIN L. DUNN, a citizen of the United States, residing at Marietta, in the county of Washington and 5 State of Ohio, have invented certain new and useful Improvements in Methods of and Apparatus for Stopping Leaks in the Casing of Oil and Gas Wells, of which the following is a specification, reference being 10 had therein to the accompanying drawing.

This invention relates to methods of and apparatus for stopping leaks in the casing of oil and gas wells without removing the casing from the wells.

15 It is customary in the oil fields to line the walls of the well with casing that is securely seated above the productive measures, in order to exclude water, mud, cavings and other materials that otherwise would enter 20 the well and would seriously and often ruinously affect the production of the oil and the operation of the well. Frequently such casing develops leaks after insertion in the well. Leaks may be through the couplings 25 or under the casing seat, or they may be caused by holes being eaten through the casing by corrosive waters, but of whatever source, the leaks must be stopped for otherwise the production of oil will be interfered 30 with to the extent that its economic value may be destroyed and thousands of wells have been destroyed in this manner.

35 Heretofore it has been the practice either to withdraw the casing to repair defects, or if the casing could not be removed or was too badly damaged, to insert an inner string 40 of pipe. A more recent practice has been to endeavor to shut off leaks by pouring mud-fluid, sand pumpings or like material behind the casing with the purpose of causing the fluid to work down the annular space between the casing and the walls of the hole or between the casing and the next larger 45 string of casing and carrying fragments of rock or other material that will clog up the leak and filter out the mud till a tight seal is formed either at the leak or in the annular space adjacent to the leak and thus prevent water or other material entering 50 through the defective parts.

The methods of withdrawing the casing and repairing it or of inserting an inner string of pipe are very expensive while the method of using mud-fluid or sand pumpings 55 frequently fails of its purpose because of

obstructive materials behind the casing that prevents the fluid from reaching the sources of trouble or because the hole through or under the casing may be too large to be clogged up readily and attempts to repair 60 the well in this manner may lead to irreparable damage by letting mud in on the productive measures.

My present invention has for its object to provide a method and means for carrying 65 out said method whereby leaks in well casings may be stopped more cheaply and effectively and without removing the casing from the well. This I accomplish by applying pressure internally of the well casing 70 and forcing the pressure out through any leak in said casing and up the annular space behind the casing, loosening bridges or obstructing material and allowing the repairing fluid to obtain access to the leaks, 75 or repairing the leak by agitating the material adjacent the leak whereby any fragments of rock or other material that would tend to clog up the leak may have the opportunity of settling back and so doing. 80

In the accompanying drawings:—

Fig. 1 is a partial vertical sectional view and side elevation of my apparatus shown in relation to a well;

Fig. 2 is a similar view showing an additional feature of my invention;

Fig. 3 is also a similar view of a part of the casing showing a modification, and;

Fig. 4 is a similar view showing another form of carrying out my invention.

90 Referring first to the apparatus for carrying out my invention, in Fig. 1, I have shown the same installed in a well and the conditions which may exist behind the well casing before pressure is applied. The numeral 1 indicates a bored well having a pit 2. A casing 3 is fitted into the well bore and terminates somewhat above the pit 2, the casing being open at its lower end and closed at its upper end by any suitable form of 95 packed casing head 4. In the present instance, I have shown an L type of head having a large discharge line 5, secured thereto with a gate valve therein operated by any suitable means, as shown at 6. A gage 7 is inserted in the discharge line between the casing head and the valve to determine the amount of pressure being exerted within the casing when the valve is closed and the apparatus is in operation. A pipe 8 is sus- 100 105 110

pended in the casing 3 through the packed casing head 4 and is supplied with suitable pressure medium, such as air or gas under pressure, through suitable connections. In 5 the supply line for the pressure medium there is a valve 10 to regulate the supply and a gage 11. The packed casing head 4 is also provided with an opening which receives means for introducing additional 10 pressure medium into the casing to assist the supply introduced through the pipe line 8 in creating sufficient pressure within the casing to force the pressure medium through the leak and agitate the material outside of 15 the casing. This means comprises a supply line 13 having a valve 12 to regulate the amount of pressure medium thus introduced into the casing.

A plug 9 is inserted in the well below the 20 casing to protect the oil measures while the leak is being repaired. In the practices of present methods of repairing leaks without removing the casing, one difficulty is the obstruction to the passage of the fluid to the 25 leak by bridges which are formed adjacent the casing between the top of same and the leak, as shown at 14 in Fig. 1. Unless these bridges are broken up the fluid cannot reach the desired destination. The present 30 method of agitating the material on the outside of the casing loosens up such obstructions or bridges and permits an obstruction or bridge to be built up adjacent the leak and thus repair the leak in this manner, or 35 the fluid is permitted to pass down to the leak if the pouring method is being used. When the fluid is employed, a conductor pipe 15 is inserted at the surface to direct the fluid in its downward course adjacent the 40 outside of the casing. The leaks in the casing are indicated by the reference numerals 16.

Referring to Fig. 2, I have shown means 45 for confining the pressure medium to a limiting area in the casing. This is desirable sometimes when the casing has more than one leak, as in this way the lowest leak may be repaired and then succeeding higher leaks. With the form here illustrated, it 50 is not necessary to have a tight casing head, the desired space in the casing being made air tight by a packer carried by the pipe 8. Any form of packer may be used, but in the 55 present instance I have shown a cup packer inverted on the pipe and comprising a swedge nipple or reducer 17, a spreader 18 and leather cup 19. In operation the pressure medium is introduced through the pipe 8 and confined in the space between the plug 9 and the cup packer whence it is forced out 60 through the leak to agitate the surrounding material, after which the pressure may be removed and the leak repaired in the manner heretofore set forth.

65 In Fig. 3 I have shown means especially

adapted for repairing large leaks in well casings. In this instance the pressure medium supply pipe is sealed at the lower end as shown at 20, and is provided with a series of openings 21, below and above which are 70 located cup packers similar to the packer described in connection with Fig. 2. In the operation of this form the pressure medium is delivered to the casing through the holes 21 and confined in the space between the two 75 cup packers, whence it is forced through the leak to agitate the surrounding material, and the process of sealing the leak effected as heretofore described.

In Fig. 4 I have shown another means par- 80 ticularly adapted for repairing large leaks in casings. In this form, as in the case of the forms shown in Figs. 2 and 3, it is not necessary to have a tight casing head. The pressure medium is introduced through the 85 supply pipe 8 which is suspended in the casing 3 and capped at its lower end by a plug similar to the plug 20 shown in Fig. 3. The pipe 8 has attached thereto, a bag 22, of any suitable material, such as canvas, leather 90 or rubber, and the space between the points of attachment of said bag is provided with openings 23 through which the pressure medium passes. In operation the pipe 8 is so positioned in the well that that part of the same to which the bag is attached will be in the locality of the leak to be repaired. The pressure medium is then turned on and rushes through holes 23 inflating the bag 95 until its sides expand flush with the sides 100 of the casing 3, thereby preventing any foreign material from entering the well through the leak 16 in the casing. Any suitable material is then introduced from the top of the well behind the casing and 105 prevented from entering the casing until the coarser materials have settled out and formed a bridge adjacent the leak, which seals the same against entrance of foreign material.

Referring now to my method of stopping 110 leaks in the casings of oil or gas wells without removing the same from the well, I first introduce a plug or bridge of any suitable kind in the well beyond the leak to protect the oil measures below. I then insert a pipe into the well through a packed casing head at the top of the casing. I then apply pressure medium to the inserted pipe whereby the water or other material within the casing 115 and above the plug may be ejected through a large discharge pipe secured to the casing head. When such materials have been removed I close the gate on the discharge pipe 120 and confine the pressure in the well. When the pressure medium in the casing is sufficient 125 to overcome the pressure outside the casing it passes through the leaks and lifts and agitates the material behind the casing. I then remove the pressure and vent the well 130.

and the material behind the casing settles back in the annular space, with the result that the leak will be sealed, providing the material behind the leak carries fragments 5 of rocks or otherwise is of such a nature that it will clog up the leak. If by this means, or by repeating this procedure the leaks are not stopped, or if it desirable to place mud- fluid, sand pumpings or other material be- 10 hind the casing to protect it against corrosion, I introduce a fluid behind the casing from the surface and work it down to the defective parts by alternately building up pressure within the casing and releasing it. 15 I sometimes find it desirable to mix with the fluid, chopped rope, straw, sawdust, sand, lead shot or other like material to aid in clogging the leaks, depending upon the character of the leak and the nature of the sur- 20 rounding material.

It is sometimes difficult to repair more than one leak at a time and I therefore carry out my method in such cases by confining the pressure to a limited area in the 25 casing, the pressure medium acting in the same manner as above stated. Again, if the leak in the casing consists of a large hole, I may carry out my method by confining the air pressure in a receptacle suspended in the 30 casing which prevents any foreign matter from entering the casing, as by forming a bridge in the manner heretofore referred to in which a fluid is introduced behind the cas- 35 ing at the top thereof and carried down to the leak.

It will be understood that I desire to comprehend within my invention such modifications as may be necessary to adapt it to varying conditions and uses.

Having thus fully described my invention, what I claim as new and desire to secure by Letters Patent is:—

1. A method of stopping leaks in oil or gas well casings consisting in inserting a 45 plug below the leak and above the oil or gas bearing measure; in introducing a pressure medium into said casing; in blowing out any water or other material in said casing; in then sealing said casing above the leak to confine the pressure medium therein; and in 50 forcing the pressure medium out through any leaks in said casing to agitate the material outside of said casing.

2. A method of stopping leaks in well 55 casings consisting in inserting a plug below the leak and above the oil or gas bearing measures; in introducing a pressure medium into said casing; in blowing out any air or other material in said casing; in then sealing said casing above the leak to confine the pressure medium therein; in forcing said pressure medium through any leaks in said casing to agitate the material outside of said casing and in then removing the pressure 60 and venting the well casing above the leak

to permit the coarser materials behind the casing to settle back and seal the leak.

3. A method of stopping leaks in oil or gas well casings consisting in inserting a 70 plug below the leak and above the oil or gas bearing measure; in introducing a pressure medium into said casing; in blowing out any water or other material in said casing; in then sealing said casing above the leak to confine the pressure medium therein; in 75 forcing the pressure medium out through any leaks in said casing to agitate the material outside of said casing; and in introducing a sealing fluid adjacent the outer wall of said casing at the surface of the 80 ground adapted to seal the leak.

4. A method of stopping leaks in oil or gas well casings consisting in inserting a 85 plug below the leak and above the oil or gas bearing measure; in introducing a pressure medium into said casing; in blowing out any water or other material in said casing; in then sealing said casing above the leak to confine the pressure medium therein; in forcing the pressure medium out through 90 any leaks in said casing to agitate the material outside of said casing; in introducing a sealing fluid adjacent the outer wall of said casing at the surface of the ground; and in then removing the pressure and venting the 95 well casing above the leak to permit the introduced fluid to seal the leak.

5. A method of stopping leaks in oil or gas well casings consisting in inserting a 100 plug below the lowest leak and above the oil bearing measures; in positioning a plug in the casing above said lowest leak; in introducing and confining the pressure medium between said plugs; and in forcing the pressure medium through the leak and agi- 105 tating the material on the outside of said casing; and in removing the pressure from that part of said casing containing the leak being repaired to permit the coarser ma- 110 terials behind the casing to settle back and seal the leak.

6. A method of stopping leaks in oil or gas well casings consisting in inserting a 115 plug below the lowest leak and above the oil bearing measures; in positioning a plug in the casing above said lowest leak; in introducing and confining a pressure medium between said plugs; in forcing the pressure medium through the leak and agitating the material on the outside of said casing; in introducing a sealing fluid adjacent the outer walls of said casing at the surface of the ground; and in removing the pressure from that part of said casing containing the leak 120 being repaired to permit the introduced sealing fluid to seal the leak.

7. A method of stopping leaks in oil or gas wells consisting in inserting a plug in said casing below a leak, and another plug 130 in said casing above said leak; introduc-

- ing a pressure medium into said casing between said plugs; in forcing the pressure medium through the leak in said casing to agitate the material on the outside of same; and in removing the pressure from that part of said casing containing the leak being repaired to permit the coarser materials behind the casing to settle back and seal the leak.
10. 8. A method of stopping leaks in oil or gas wells consisting in inserting a plug in said casing below a leak, and another plug in said casing above said leak; introducing a pressure medium into said casing between said plugs; in forcing the pressure medium through the leak in said casing to agitate the material on the outside of same; introducing a sealing fluid adjacent the outer wall of said casing at the surface of the ground; and in removing the pressure from that part of said casing containing the leak being repaired to permit the introduced fluid to seal the leak.
9. In an apparatus of the character described, the combination with a casing, 25 means for introducing a pressure medium into said casing, and means for confining said pressure medium in said casing and forcing it through a hole in said casing to agitate the material on the outside of said casing, 30 of a plug for preventing the pressure medium from coming in contact with the oil bearing measures.
10. In an apparatus of the character described, the combination with a casing, a 35 pipe suspended in said casing adapted to carry a pressure medium into said casing, and a plug carried by said pipe whereby the pressure medium may be retained in said casing below said plug, of another plug inserted below said casing and above the oil or gas bearing measures to prevent the pressure medium from having access thereto.

In testimony whereof, I affix my signature.

IRWIN L. DUNN.
